(57) **CLAIM**

I claim the ornamental design for a back cavity plate for a golf club head, as shown and described.

DESCRIPTION

FIG. 1 is perspective view of a back cavity plate for a golf club head showing my new design; and, FIG. 2 is an elevational view of the back cavity plate shown in FIG. 1.

The broken line showing of portions of a golf club head is for illustrative purposes only and forms no part of the claimed design.
